UNITED STATES PATENT OFFICE.

CHARLES B. NICHOLS, OF SPRINGFIELD, AND FRANK E. SHEPHERD, OF CHICAGO,
ILLINOIS.

RAILWAY-TIE.

1,048,199.

Specification of Letters Patent.

Patented Dec. 24, 1912.

Application filed April 22, 1912. Serial No. 692,496.

To all whom it may concern:

Be it known that we, CHARLES B. NICHOLS and FRANK E. SHEPHERD, citizens of the United States, and respectively residents of the city of Springfield, in the county of Sangamon and State of Illinois, and the city of Chicago, in the county of Cook and State of Illinois, have invented a new and useful Railway-Tie, of which the following is a specification.

The invention relates to composite ties for railways.

The general purpose of the invention is: to provide a composite railway tie comprising separable elements each having distinguishing characteristics as hereinafter set forth, the tie as a whole having great rigidity and affording a cushion support for the track rails adapted to minimize the jar and noise of cars running on the track.

More specific purposes are: to provide a one-piece main structure shaped to form at the ends of the tie pockets adapted to receive blocks supporting the rails; to provide rail supporting blocks adapted to fit in the pockets indiscriminately; to provide means for supporting the block and clamping them in the pockets to prevent splitting of the blocks; and to provide a reinforcement between the blocks increasing the weight and rigidity of the tie.

With these ends in view, the invention consists in the novel features of construction and combinations of parts shown in the annexed drawing and hereinafter described and finally recited in the claims.

Figures 1 and 2 are respectively a top plan and a side elevation of the tie; Fig. 3 is an enlarged vertical section on the line X. X. of Fig. 2; and Fig. 4 is an enlarged vertical section on the line Y. Y. of Fig. 2.

Similar reference characters designate like parts in the different views.

The frame of the tie, designated as a whole by the numeral 1 is a single bar of angle iron bent as shown. The angle bar 1 has a vertical member 1^a preferably about six inches wide and a horizontal member 1^b preferably about two inches wide. The bar is bent to form rectangular pockets 2 having vertical walls 2^a formed by the vertical member of the bar 1, and internal horizontal flanges 2^b formed by the horizontal member of the bar 1. The bar 1 is bent back on itself so that in that part

of the bar which is between the pockets the ends of the bar are adjacent to each other and the edges of the adjacent parts of the member 1^b are parallel and close to each other and in conjunction with the member 60 1^a form a channel 6 extending from one pocket to the other. The bar 1 is pierced by transverse holes 3, accommodating bolts 4 or equivalent means, for connecting the parts. The blocks 5 fit snugly in the pockets 2 65 and the lower ends of the blocks are supported on the flanges 2^b and prevent the blocks from being pushed out of the pocket.

The blocks are preferably of wood treated with creosote or other preservative and 70 dipped into boiling asphaltum. The pockets are all the same size and the blocks are all the same size, so any block will fit in any pocket. The blocks fit snugly in the pockets so that when the nuts on the bolts 4 75 are tightened they will cause the sides of the pockets to bear firmly against the sides of the blocks and securely hold the blocks.

When the blocks are in place in the pockets and the nuts on the bolts 4 are tightened 80 the channel 6 formed by the parallel parts of the bar 1 between the pockets 2 will be filled with a filler 7 of cement or concrete or other suitable material, to stiffen and strengthen the central part of the tie. If 85 the tie is to be used on an elevated structure, the filler 7 will preferably consist of a composition of saw dust and asphaltum, or equivalent sound-deadening material. Chairs 8 resting on the blocks 5 support the 90 rails. Spikes 10 or equivalent means, securely connect the chairs and rails with the blocks. The side walls of the pockets bearing firmly against the sides of the blocks prevent the blocks from splitting while the 95 spikes are being driven.

If it be desired to remove a worn or defective block, the bolts 4 adjacent to the pocket in which the block is contained will be removed to relieve the pressure of the 100 side walls of the pocket against the sides of the blocks; the block will then be lifted out of the pocket, a new block will be placed in the pocket, the bolts will be tightened to keep the new block in the pocket and the 105 spikes will be driven into the block to connect the chair and rail, or rails, with the block.

The present invention contemplates the 110 economical use of wood to form the rail-

supporting parts of ties, wood being best adapted for that use on account of its yielding nature and the facility with which spikes may be driven into it.

5 The pockets arranged to clamp and prevent splitting of the blocks admit of the use of relatively small blocks, so that the wood may be used most economically. The metal and cement parts of the tie are very durable and the more perishable parts can be readily replaced.

Compared with the ordinary wood ties, the first cost of the composite tie is reasonable, the cost of maintenance is relatively small, and the life of a composite tie is longer than the life of a wood tie.

15 Having fully described our invention, what we claim as new and desire to secure by Letters Patent is:

20 1. In a composite tie, an angle bar bent to form internally flanged pockets and a two-ply central part between said pockets;

in combination with rail-supporting blocks resting on the flanges of said pockets.

2. In a composite tie, an angle bar bent 25 to form internally flanged pockets and a channel between said pockets; in combination with blocks supported on the flanges of said pockets and a filler occupying the channel between said pockets. 30

Signed by me, CHARLES B. NICHOLS, at Springfield, Illinois, October 31st, 1911, and signed by me, FRANK E. SHEPHERD, at Chicago, Illinois, October 28th, 1911.

CHARLES B. NICHOLS.
FRANK E. SHEPHERD.
